UNITED STATES PATENT OFFICE.

WARREN E. WALTERS AND MARY E. WALTERS, OF LOS ANGELES, CALIFORNIA.

INDICATOR AND POWER DEVICE THEREFOR.

1,075,882.

Specification of Letters Patent.

Patented Oct. 14, 1913.

Application filed August 7, 1912. Serial No. 713,796.

To all whom it may concern:

Be it known that we, WARREN E. WALTERS and MARY E. WALTERS, citizens of the United States, residing at Los Angeles, in the county 5 of Los Angeles and State of California, have invented certain new and useful Improvements in Indicators and Power Devices Therefor, of which the following is a specification.

10 This invention relates to improvements in power driven mechanisms in which a visible, movable part, indicator or the like is given motion by means of a power device which is active for moving the movable device or indicator, without the use of gearing 15 or like moving parts or the use of any parts which will produce a noise of any kind.

It is an object of the invention to provide a traveling or moving device with hidden 20 power mechanism capable of moving said device without working parts or mechanism.

It is also an object of the invention to provide a moving indicator of magnetic or non-magnetic material, and a motor or power 25 device of magnetic character for actuating the same.

It is a still further object of the invention to provide a mechanism in which magnetic or non-magnetic materials may be moved 30 through the controlled changing polarity of a magnetic mechanism actuated by an alternating current or one in which the current is broken or interrupted.

In the accompanying drawings, forming 35 part of this specification, Figure 1 is a side elevation of a mechanism embodying the features of the present invention, the casing of the power device being shown in section. Fig. 2 is a top plan view of the said power 40 device shown in Fig. 1. Fig. 3 is a perspective view of one of the plates or leaves employed in the laminated magnet of the power device. Fig. 4 is a vertical, sectional central view taken transversely through a movable 45 indicator and the support upon which it rests, the power device being shown in end elevation. Fig. 5 is a detail view showing a portion of a movable wheel and a power device for actuating the same, having a series 50 of poles curved to fit the periphery of the wheel. Fig. 6 is a fragmentary, detail view in elevation of a part of the periphery of a rotating wheel such as may be employed in connection with this invention.

55 The present invention is designed to afford a silent and hidden means for actuating and

turning a movable part or indicator, the power means being usually hidden from view and operating without noise or motion so that the movable part or indicator would seem to be actuated in a mysterious manner to the observer. The device is especially well adapted for use as an advertising medium, the movable part being employed with its mysterious actuation, to carry said advertising material, and to bring the same to the attention of observers attracted by its peculiar action, and when applied in that field of usefulness, is an improvement on the prior Patent, No. 962,069, issued to Warren E. Walters and Harry S. Fitzgerrell, June 21, 1910. Since the mechanism is especially well adapted for advertising purposes, the drawings illustrate mechanism adapted for that purpose, and the invention will now be described, reference being had thereto.

In the said drawings, 1 indicates a wheel or circular member, 2 a frame or support therefor, 3 a base upon which the said frame rests, while 4 indicates a power device with in said base.

The form of indicator shown in Fig. 1 is usually constructed with a rim portion of glass or other non-magnetic material carried by spokes 5, also preferably of glass or some 85 non-magnetic material. The said spokes are usually made hollow or tubular, and movable, solid or liquid substances, such as for instance metallic balls 6, are movably mounted therein. The spokes are carried by any 90 suitable hub portion 7 which is mounted upon ball or other bearings 8 as clearly shown in Fig. 4, the said bearing being carried by an adjustable shaft 9. The said shaft is supported upon adjusting screws 10 95 which are carried by the frame 2. The said frame 2 preferably rests upon glass or other non-magnetic feet as indicated at 11. The wheel is provided with any desired means for carrying advertising material or other 100 information, such means comprising usually disks 12, which are pivotally mounted between standards 13 carried by the rim of the wheel 1. The said standards project inwardly to pivotally support the disks and 105 the disks are usually weighted as at 14 so as to cause them to remain in upright position for a proper showing of the information placed thereon, no matter what the movement of the wheel 1 may be. The balls 6 or 110 other movable substance as quicksilver 6^a, shown in Figs. 1 and 4 may run back and

forth in the tubes through the action of gravity in accordance with the position of each tube.

The power device 4 forms an important feature of the invention and constitutes a power member operating without movable parts and consequently without noise of any kind. The said power device is preferably made up of a laminated magnet having a central pole 15 and outer poles 16 and 17. The said magnet is preferably of the laminated type, being constructed of a series of thin metallic plates 18, usually of the shape shown in Fig. 3. In placing the plates together they are generally dipped in a solution of silica or water glass so as to become coated therewith and then applied side upon side as shown in the drawings. A central ventilating or air space 19 is usually provided between the central plates of the magnet as clearly shown in Fig. 2 for preventing the tendency to heating when in use. The central pole 15 is surrounded by a coil 20 usually formed of properly insulated wire 21 and wrapped with any suitable insulating material or with oiled silk. The poles 15, 16, and 17 are provided with recesses 22 formed near one side of each pole as shown in Figs. 1 and 2 of the drawings. In this manner small spur poles 23 are provided at the sides of the main poles and these small poles 23 are surrounded by small coils 24. The coils 24 are preferably made of wires properly insulated and having their ends soldered at 25 or otherwise fusibly connected so as to safeguard the power device and prevent its being burned out. In the event of an excessive heating of the mechanism, the fusible connection 25 will be melted and the other portions of the power mechanism thus be saved from injury. The laminated magnet is preferably bound together at 26 by any suitable material as for instance a band of copper or similar material. The ends of the coil 21 are led to any suitable source of electricity and may be connected with a plug of ordinary construction so as to fit into any incandescent lamp socket. In this manner the ordinary house current employed may be caused to flow through the coil 21, and such current being an alternating current continually changes the polarity of the poles 15, 16 and 17. The small coils 24 act as lagging coils and retard the change of polarity at the sides of the poles with the result that the vibration in the current thus set up operates to rotate the wheel 1, the vibrations of the current causing the balls 6 to pass the motor in succession as each enters the magnetic field formed by the power device. The peculiar action of the currents set up in the power device will rotate a wheel or other device.

It will be seen that the motor operates

without any moving parts and that it can be entirely hidden from view, and may even be inclosed and sealed up within the support 3.

As shown in Fig. 5, the motor or power device may comprise a magnet 30 having a number of outside poles 31 and an inside pole 32 which is surrounded by a coil 33 similar to the coil 20 heretofore described. As shown in Fig. 5 the magnet may be made to conform to the peripheral shape of a wheel as 34. The poles of the magnet are all kerfed in their ends as at 35, and lagging pieces or plates 36 are set therein, all of said plates being extended in the same direction and mounted upon the same corresponding corners of the different poles. In providing the wheel with means which may be acted upon by the currents set up in the motor, the peripheral portion of the said wheel 34 may have embedded therein metallic wires 37 or plates as desired. In this instance the wheel is usually made of opaque material, so that the attractive member carried by the wheel is not observable. A wheel of this kind may be made to rotate in a horizontal plane or in a vertical plane as desired, within the scope of the invention.

In employing large wheels, it is found of advantage to use an inner metallic tire or band 55 as shown in Figs. 4 and 6, and to place outside the same a second rim or tire 56, usually made of brass or non-magnetic material. The said outer rim is provided with a series of perforations 57, arranged at intervals so that the inner metallic rim 52 may be subjected at intervals to the attraction of the fields of the power device.

It will be observed from the above description that a wheel or disk of comparatively large dimensions may be employed, a good result being obtained by embedding in the periphery of the wheel or connecting therewith in some manner solid or liquid attraction pieces or substances, bars or rims so that the magnetic fields extending from the poles of the magnet, and which are moved to one side by the lagging pieces or coils upon the poles thereof will continuously rotate the said wheel or disk.

It will also be observed that the device is especially well adapted for use with indicators, advertising mechanisms or like places where it is desired to produce motion without any apparent means distinguishable to the usual observer, and without working parts or connections, gears or any noise due thereto.

The size of the indicator or movable part employed may be varied to suit the circumstances to which it is adapted, and may of course be made in any form, configuration or shape desired. The mysticism of the movement of such an indicator may also be increased by the use of non-magnetic material

in its formation, and by mounting the device upon a glass plate or mirror upon glass feet or supports so that it is evident to the observer that there are no ordinary electric connections employed or other visible means for the transmission of an actuating energy.

The device may be made in portable form and the supporting base may have the power mechanism sealed within the same so as to preserve the same from examination by the inquiring observer.

It will also be observed that the power device not only operates without gearing, parts or mechanism connecting it with the member or indicator moved, but that the speed of the driven part may be increased or diminished without any intermediate parts and by merely arranging the power device closer to the moving part. The speed may of course be diminished by separating the parts.

The device of the present invention lends itself admirably to the advertising of various kinds of goods and wares, for it will be readily understood that any mechanism having a movable part may be arranged in a

show-window or other place, with an unseen power device such as above described, for turning or moving it. Thus, vehicles may be advertised, sewing machines, their moving parts being operated by a hidden power device.

What is claimed is:

A device of the class described, comprising a movable member, a power member having a magnet formed with poles projecting therefrom, a coiled conductor surrounding one of said poles for passing a current of electricity about the same, each of said poles having kerfs in their ends near one edge thereof, coils mounted in said kerfs and having fusible connections and means for separating and supporting the movable member from the said power member.

In testimony whereof, we have hereunto set our hands, in presence of two witnesses.

WARREN E. WALTERS.
